UNITED STATES PATENT OFFICE

WILLET E. STARK, OF EAST CLEVELAND, OHIO, ASSIGNOR TO THE BRYANT HEATER & MANUFACTURING COMPANY, OF CLEVELAND, OHIO, A CORPORATION OF OHIO

BOILER SECTION

Application filed March 28, 1928. Serial No. 265,321.

This invention relates to improvements in water heaters, and more particularly to an improved construction in the water heater sections of the water heater.

5 The primary object of the invention is to provide hollow water heater sections in which there is maintained a positive circulation of water to thereby render the water heater more effective in operation.

10 Another object of the invention is to maintain the surface of the water within the water heater sections relatively quiet, to thereby afford a more effective liberation of the steam therefrom.

15 Another object of the invention is to provide a water heater section which is simple in construction, efficient in operation, and inexpensive to manufacture.

A still further object of the invention is 20 to provide a water heater section provided with improved means for more advantageously and effectively causing the heated gases to be distributed over the surfaces of the water heater section.

25 With the objects above indicated and other objects hereinafter explained in view, my invention consists in the construction and combination of elements hereinafter described and claimed.

30 Referring to the drawings,

Figure 1 is a vertical elevational view of one of the water heater sections, having portions thereof broken away to show the details embodying the present invention.

35 Figure 2 is a front elevational view of a water heater showing the manner in which the sections are assembled.

Figure 3 is a transverse vertical sectional view of one of the water heater sections.

40 Figure 4 is a top plan view of a water heater section.

In the drawings there is illustrated a water heater of usual construction, comprising a base 10 usually of cast iron, the upper portion 45 of which is adapted to receive and sup-

port a plurality of water heater sections 11. While four water heater sections are here disclosed as constituting the water heater, it should be understood that any desired number of sections may be employed depending upon the requirements of the water heater.

The base 10 contains and supports a plurality of burners 12 which are positioned adjacent the lower surfaces of the sections 11, and said burners are supplied with fuel from any suitable source through the pipes 13.

Each water heater section 11 is provided with an inlet opening 14 for the admission of cold water from any suitable source, being located at the lower corner of the water heater section 11, while a steam outlet opening 15 is provided at the upper corner of the water heater section 11 diametrically opposite from the inlet opening 14. Each of these water heater sections 11 is adapted to be positioned side by side upon the base 10, and the inlet and outlet openings 14 and 15, respectively, of each section are adapted to 70 abut to provide a continuous passageway for the incoming water and for the outgoing steam. These sections are suitably clamped together by transversely positioned bolts 16 disposed within grooves 17 at the upper and lower portions of the sections adjacent the inlet and outlet openings.

The usual cover 18 is supported upon the upper portions of the water heater sections 11, and has a suitable opening 19 through 80 which the smoke and gases can escape.

Upon the outer vertical sides of the water heater sections are a plurality of laterally extending lugs 20 disposed in horizontal rows, the lugs in each row being in staggered relation with respect to the lugs of each adjacent row. These lugs are provided with diverging surfaces upon their under sides and are adapted to deflect the hot gases to cause the latter to travel upwardly between the 85 90

heater sections in a tortuous path. The diverging surfaces upon the undersides of the lugs extend preferably at an obtuse angle, as it has been found that by so forming the 5 diverging surfaces of the lugs that the heated gases are more efficiently distributed over the entire surfaces of the water heater sections 11 and caused to travel in a more circuitous path, thereby obtaining substantial 10 ly a maximum in heating efficiency.

In the ordinary type of water heater section employed in connection with water heaters the section is ordinarily hollow, and the water which is admitted to the lower portion 15 of the section is heated by the flame of the gas burner. The heated water then rises to the top or upper portion of the heater section and the steam is liberated therefrom. It will, therefore, be seen that there is no 20 positive circulation of the water within the water heater section. The failure of this water to circulate within the section is quite a disadvantage and affects materially the efficient operation of the water heater for 25 the purpose for which it is employed.

To create a positive circulation of the water within the water heater section 11 there is provided a transversely extending baffle plate 21 formed integral with the sides of 30 the water heater section. The baffle plate 21 extends substantially parallel with the bottom surface of the water heater section 11, and preferably the bottom of the section and the baffle plate 21 extend at an incline 35 from the back of the water heater section 11 toward the front. The baffle plate 21 terminates short of the front and rear walls of the water heater section 11, so as to provide suitable passageways therebetween. The 40 space between the rear end of the baffle plate 21 and the rear end of the water heater section 11 is considerably smaller than the space between the underside of the baffle plate 21 and the bottom of the heater section 45 11 for a purpose to be later described.

At the upper portion of the water heater section 11 is a second baffle plate 22 extending transversely of the water heater section and preferably formed integral with the sides 50 thereof. This baffle plate 22 extends at an incline from the front of the water heater section towards the rear thereof and is considerably less in length than the baffle plate 21. The baffle plate 22 at the front end terminates short of the front wall of the water heater section 11 for the purpose of providing a suitable passageway for draining the water from the water heater section 11 when desired. The baffle plate 22 is 55 preferably located just beneath the normal level of the water within the water heater section 11 and functions additionally to maintain the surface of the water relatively quiet, to thereby effect a more efficient liberation of 60 the steam therefrom.

The circulation of the water within the water heater section 11 is effected in the following manner: As the cool water enters the water heater section through the inlet opening 14, it is heated by the flame of the gas 70 burner 12, and tends to circulate in substantially a horizontal path toward the front of the water heater section, due to the fact that there is more space between the baffle plate 21 and the bottom of the section than there is 75 between the rear edge of the baffle plate 21 and the rear wall of the water heater section. The upward inclination of the bottom of the water heater section and the baffle plate encourages this tendency. As the heated water passes from under the front end of the baffle plate 21 it rises substantially vertically in a more or less well defined stream until it reaches the upper baffle plate 22, when it is directed in substantially a horizontal path 80 toward the rear of the water heater section 85 due to the inclination of the baffle plate 22.

The column of water at the rear of the water heater section 11 is somewhat cooler and, therefore, slightly heavier than the column 90 of water at the front of the water heater section. This gives the water a definite circulatory motion and thus renders the section much more efficient in its operation.

While I have described the preferred embodiment of the invention, it is to be understood that I am not to be limited to the specific construction disclosed herein, as changes and modifications may be resorted to without departing from the spirit of the invention as 95 defined in the appended claims.

Having thus described my invention what I claim is:

1. A section for boilers and the like comprising a hollow body member having an inlet opening and an outlet opening, a baffle extending transversely of said member and substantially parallel with the bottom thereof, there being passageways at opposite ends of said baffle, the cross section of the rear passageway being less than the cross section of the space between the baffle and the bottom of said member, and a second baffle extending transversely of said member and positioned above the latter but adjacent the normal water level of said member.

2. A section for boilers and the like comprising a hollow body member having an inlet opening and an outlet opening, a forwardly inclined baffle extending transversely of said member and positioned adjacent the inlet opening, there being passageways at opposite ends of said baffle, and a second baffle inclined rearwardly and positioned adjacent the outlet opening and the water level and adapted to retard the upward flow of liquid within the body member.

3. A section for boilers and the like comprising a hollow body member having an inlet opening and an outlet opening, a baffle in-

clined forwardly and positioned adjacent the bottom of said body member, a passageway at the rear portion of said baffle of smaller area than the passageway beneath said baffle,
5 a passageway at the forward portion of said baffle, and a second baffle inclined rearwardly and positioned above the forward end of said first-mentioned baffle but adjacent the water level.

10 In testimony whereof, I hereunto affix my signature.

WILLET E. STARK.
